UNITED STATES PATENT OFFICE.

ORRIE F. PENNYPACKER, OF YOUNGSTOWN, OHIO ASSIGNOR OF ONE-HALF TO
CHARLES A. HARPMAN, OF YOUNGSTOWN, OHIO.

OPEN-HEARTH FURNACE.

Application filed April 18, 1921. Serial No. 462,175.

To all whom it may concern:

Be it known that ORRIE F. PENNYPACKER, citizen of the United States of America, residing at Youngstown, in the county of 5 Mahoning and State of Ohio, has invented certain new and useful Improvements in Open-Hearth Furnaces, of which the following is a specification.

This invention relates to open hearth 10 furnaces, which are adapted to conserve the heat, and add to the temperature of furnaces, and particularly those which operate at high heats.

The arrangement and construction of this 15 furnace is related to the type known as single surface generators, in which the heat of the outgoing gases is applied to and absorbed by the checkers, walls, etc., and given back to the incoming gases from the same 20 surfaces of the checkers, walls, etc. which receive the heat.

The principal object of this invention is to provide a furnace with a water-cooled 25 manifold positioned underneath a water-cooled port, or other ports constructed as known to the art. This water-cooled manifold is provided with a plurality of air distributors positioned so that the same lead into the sides of said port, and directing 30 the incoming air in a general direction towards the inner opening of said port, and at the same time each of the several openings directing the incoming air in varying angles in relation to the general direction 35 of the port.

Another object of the invention is to provide a second water-cooled manifold positioned longitudinally underneath the above described manifold, and forming a portion 40 of the outer gas uptake wall. The several openings of this manifold directing the incoming air in a general inward and upward direction, but each outlet of the same directing said air at varying angles.

A still further object of the invention is to carry compressed or fanned air through 45 a channel by means of a straight or tortuous path within the outer gas uptake wall. This is done in order to utilize the heat in 50 the said wall to pre-heat the air, and at the same time to relieve said wall of extreme temperatures which are detrimental to the long usage of such walls when of solid or ordinary construction.

The furnace is otherwise constructed 55 along ordinary lines common to the art, that is, the furnace is also provided with an air regenerator or checker chambers leading intake above the port.

In order to simplify the description of my 60 invention, I will describe and illustrate it in connection with open hearth steel melting furnaces, but it is, of course, equally applicable to heating furnaces of any and all characters for the purpose of conserving 65 the heat and particularly in introducing forced air into the port, and giving the same an inward and whirling motion, thereby effectively mixing pre-heated forced air with producer gas or other combustibles. 70

With these and other objects in view the invention consists in the novel arrangement and construction of parts which will be hereinafter more fully described and pointed out in the claims. 75

In the drawing accompanying this specification, a preferred form of an arrangement, according to my invention, is shown as adapted to an open-hearth furnace of well known construction. 80

Figure 1 is a detail sectional view of one end of the furnace.

Figure 2 is a detail view.

Figure 3 is a detail view.

Figure 4 is a detail sectional view. 85

By referring to Figure 1 it will be seen that I have provided an ordinary bath bottom 1 which is constructed along the lines well known to the art. Upon the gas uptake wall 2 and the division wall 3 rests a water-cooled manifold 4 provided with a plurality of air intake members 5 so arranged as to direct forced air into the sides of a port, giving the air an inward and whirling motion. Each of these air intake 90 members 5 giving the forced incoming air a different inward direction. 95

By referring to Figure 2 it will be seen that I have provided two water-cooled manifolds 4 which support partially the port 6. Directly underneath the water-cooled manifolds 4 I have provided a second water-cooled manifold 7 forming a portion of the gas uptake wall 2. Centrally located in this water-cooled manifold 7 I have provided a plurality of forced air inlets 8 so arranged as to direct the incoming air into the gas uptake 9 in an upward and inward 105

direction. Each of the several forced air inlets 8 positioned so as to direct the incoming air in a different general direction.

By referring to Figure 4 it will be seen that the water-cooled manifolds 4 are provided with a water inlet 10 and outlet 11, and with an air inlet 12 leading to the air intake members 5, which in turn lead the forced air into the port 6.

10 In tracing the movement of the forced incoming air the same is introduced into the straight or tortuous channel 13 within the gas uptake wall 2. The said air passing through valves 14 and 15. The valve 14 15 controlling the passage of the air into the manifolds 4. The valve 15 controlling the passage of the air into the second manifold 7.

By referring to Figures 1 and 2 it will be seen that I have provided overflow pipes 16 20 which may be of ordinary construction.

In water-cooling the secondary manifold 7 any desired openings may be resorted to so that the water-cooling system as described in reference to the water-cooled manifold 4, 25 may be utilized.

If desired, the air may be forced into the furnace by way of both the valves 14 and 15, or through either one of the same. It is understood that the furnace in its general construction conforms to the ordinary furnace 30 known to the art, and that the outer surface 17 of the division wall 3 forms one wall of an air uptake of ordinary construction, which introduces air above the port at the 35 point 18.

What I claim is:

1. In a device of the class described, an arched port provided with a plurality of side inlets for directing air in different directions within said port, two manifolds directly underneath the side walls of the port, a plurality of inlets opening into said port, said inlet directing air in an inward and varying direction, a secondary manifold, air inlets positioned in the same, said inlets di-

recting the air in an inward and upward direction, but each inlet varying the direction as related to the other inlets, a channel within the uptake wall of a gas uptake, two valves controlling the air leading from 50 said channel, means for circulating water through said manifolds, substantially as described for the purpose set forth.

2. In a device of the class described, having in combination with an arched port 55 provided with a plurality of side inlets for directing air in different directions within said port, a furnace provided with an air uptake introducing air in the above said port, two manifolds directly underneath the 60 side walls of a port, a plurality of inlets opening into said port, said inlets directing air in an inward and varying direction, a secondary manifold, air inlets positioned in the same, said inlets directing the air in an 65 inward and upward direction, but each inlet varying the direction as related to the other inlets, a channel within the uptake wall of a gas uptake, two valves controlling the air leading from 70 said channel, means for circulating water through said manifolds, substantially as described for the purpose set forth.

3. In a device of the class described, the combination of an arched port provided with 75 a plurality of side inlets for directing air in different directions within said port, two manifolds positioned under said port, air inlets within said manifolds leading into said port with a secondary manifold provided with a plurality of air inlets leading 80 to a gas uptake channel, means for water cooling said manifold, substantially as described for the purpose set forth.

In testimony whereof I affix my signature. 85

ORRIE F. PENNYPACKER.
